UNITED STATES PATENT OFFICE

1,934,139

MEANS FOR SHARPENING SAFETY RAZOR
BLADESEdwin George Pavitt, London, England, assignor
to Newton Sales Company Limited, London,
EnglandApplication September 19, 1930, Serial No.
483,059, and in Great Britain September 25,
1929

1 Claim. (Cl. 51—198)

This invention relates to means for sharpening safety razor blades.

The invention consists broadly in the provision of a strop or hone having a grooved surface and means for ensuring that the blade during the operation of stropping will automatically adopt the correct angle in relation to the grooved surface of the strop or hone.

The strop or hone may have abrading material applied to its surface so as to fill the grooves.

A further feature of the invention is the provision of a clip or holder by means of which the blades can be held so as to adopt automatically the correct angle in relation to the strop or hone.

In order that the invention may be more clearly understood one example of the invention will now be described with reference to the accompanying drawings, wherein:—

Figures 1, 2 and 3 are plan views of the strop or hone showing different forms of the grooved surface;

Figure 4 is a side elevation of a modified form of strop or hone;

Figure 5 is a side elevation of the preferred form of clip or holder with a razor blade in position for sharpening;

Figure 6 is a perspective view of the strop or hone as shown in Figure 4 in operation; and

Figure 7 is a perspective view of a further form of holder with a blade in position for sharpening.

In these drawings the strop or hone, which may be made of a suitable material of a hard

nature but preferably one which can be moulded, such as a synthetic resin, has a grooved surface 2 secured to a base or back plate 3 which is provided with a hole 4 or like device for hanging the strop or hone when not in use.

The grooved surface of the plate 2 may be treated with any suitable abrading material, such for example as carborundum paste. The grooves formed on the plate 2 may be of any convenient form but the most effective form of grooves have been found to be of curved, herringbone, or serpentine design, as shown in Figures 1, 2 and 3, and arranged in such a manner that a razor blade when being sharpened will pass across them obliquely.

Figures 4 and 6 of the drawings show a modi-

fied form of strop or hone made in accordance with the present invention and curved to a suitable radius of curvature so that when a razor blade 7 is laid upon the grooved surface 2 of the strop or hone and pressure is applied, the edges 10 of the blade 7 will automatically adopt the proper angle to the grooved surface 2 of the strop or hone for sharpening, thus avoiding the necessity for a holder for the blade.

When a strop or hone as shown in Figures 1, 2 and 3 is employed, a holder for the blades is provided which may be in the form of a clip or holder (see Figure 5) having gripping jaws 5 and 6 at one end adapted to be opened to enable the blade 7 to be inserted, by pinching together or compressing the two arms 8 and 9, but the arms 8 and 9 are disposed at such an angle that when the clip is laid upon the grooved surface 2 of the strop or hone, and light pressure is applied, the edge 10 of the blade 7 will be in contact with the grooved surface 2 of the strop or hone at the proper angle to ensure correct sharpening. This clip may be provided with means for ensuring the correct positioning of various types of blade in the gripping jaws 5 and 6.

The clip or holder for holding the blades may be of wedge-shaped formation, as shown in Figure 7, and provided with bosses 11 and 12 or the like to hold the various types of blade in correct sharpening position. The wedge-shaped holder may also be provided with a ridge or flange 13 for facilitating the moving thereof during the operation of sharpening.

In operation with strops or hones of the flat type, the blade 7 is arranged between the jaws 5 and 6 of the clip or holder which is then laid on the grooved or abrading surface 2 of the strop or hone, the strop being arranged to be flat upon a table. The holder with the blade in position is then moved along the grooved surface 2 of the strop with a little pressure, which operation sharpens one side of one edge of the blade 7. The clip is then turned over and the operation repeated on the other side of the same edge. The blade may then be reversed in the clip or holder and the other edge similarly treated. When using a curved strop or hone, as illustrated in Figure 4, it is only

necessary to place the blade in position and apply light pressure to its centre, as illustrated in Figure 6. A few reciprocations of the blade in both directions will, under these conditions, 5 effect the desired sharpening.

What I claim is:

A device for sharpening razor blades con-

sisting of a hard plastic inflexible plate of synthetic resin, said plate having an unyielding working face provided throughout its whole area with closely arranged grooves, and abrading material filling and retained in said grooves. 80

CERTIFICATE OF CORRECTION.

Patent No. 1,934,139.

November 7, 1933.

EDWIN GEORGE PAVITT.

It is hereby certified that the above numbered patent was erroneously issued to "Newton Sales Company Limited, of London, England," as assignee of the entire interest in said invention, whereas said patent should have been issued to the inventor said "Pavitt" and the "Newton Sales Company Limited, of London, England," as assignee of one-half interest only as shown by the records of assignments in this office; and that the said Letters Patent should be read with this correction therein that the same may conform to the record of the case in the Patent Office.

Signed and sealed this 12th day of December, A. D. 1933.

F. M. Hopkins
Acting Commissioner of Patents.
